E. L. NORFOLK.

Supplying Oil Gas Retorts.

No. 40,058.

Patented Sept. 22, 1863.

John O. Bassett
Wm. H. Harrison

E. L. Norfolk

UNITED STATES PATENT OFFICE.

EDWARD L. NORFOLK, OF SALEM, MASSACHUSETTS.

IMPROVED DEVICE FOR SUPPLYING GAS-RETORTS WITH LIQUIDS.

Specification forming part of Letters Patent No. 40,058, dated September 22, 1863.

To all whom it may concern:

Be it known that I, EDWARD L. NORFOLK, of Salem, Massachusetts, have invented an Improved Device for Supplying Gas-Retorts with Liquids, of which the following is a specification.

The nature of my invention consists in a new method of supplying gas-retorts with hydrocarbon used in illuminating gas manufacture, by means of a vessel or chamber so constructed and arranged with reference to the retort in which it is to be decomposed that the pressure exerted by the gas shall be equal upon the chamber and retort, by means of suitable connecting-pipes, as described in the drawing, and thus allow the hydrocarbon to flow into the retort in a continuous stream. The difficulty which this apparatus is designed to overcome is that of maintaining a regular supply of hydrocarbon under any pressure. In the ordinary way, by the use of siphons, any sudden change of pressure throws the hydrocarbon out of the siphon, unsealing the gas and allowing it to escape, and the siphon being usually near the fire the hydrocarbon is inflamed, thus making its use dangerous in many places. Besides, the objection of the disagreeable smell of most hydrocarbons, when exposed to the atmosphere, is entirely avoided by this apparatus, and it may be applied to all kinds of hydrocarbon-gas manufacture, and is especially adapted to the apparatus used in the manufacture of water-gas, in which it is in successful operation, and by its use gas making can be conducted in the most confined locality with safety and freedom from the annoying odor of the hydrocarbons; and in the use of volatile hydrocarbons, or those which require to be heated to make them limpid, it is economical from the fact of its confining and saving these products of evaporation. It also diminishes the labor required from its requiring no watching or attention after once being adjusted.

To enable others skilled in the art to make and use my invention, I will proceed to describe, the same reference being had to the

drawing, which represents in section this chamber applied to upright retorts.

A is the chamber, which is placed above the retorts B, and is usually supported by the furnace C, though its position may be changed to meet the requirements of any locality. It is constructed of metal, perfectly air-tight, and made of any required size. It is provided with any suitable means of filling with hydrocarbon, either at intervals as the supply is exhausted, as at H, or a continuous supply may be kept up by means of a pump connecting with a reservoir of the hydrocarbon, and it may be provided with a glass tube, D, to be placed on the side, to serve as an indicator of the height of the liquid in the vessel, this gage being connected at the top and bottom of the box in nearly the same manner as the gages in use on steam-boilers.

From the top of the chamber above the level of the hydrocarbon, the pipe E is connected with the top of the retort, which opens a communication and of course admits the same pressure upon both the chamber and the retort. Communication being opened between the lower part of the chamber and the retort B by the pipe F, a continuous supply of hydrocarbon will be maintained, which may be controlled by the stop-cock G.

The pipes connecting the retort and chamber may be made of any size desired, but should be in proportion to the quantity of hydrocarbon required and the size of the apparatus. The cock I is placed in the pipe E, to be closed when filling through the funnel and cock H.

Having thus fully described the nature of my invention, what I claim therein as new, and desire to secure by Letters Patent, is—

Maintaining a regular supply of hydrocarbon for gas purposes, by means of the chamber A and connecting-pipes E and F, or their equivalents, the whole operating in the manner and for the purpose set forth.

E. L. NORFOLK.
